UNITED STATES PATENT OFFICE

2,652,955

CALK GUN AND CARTRIDGE ADAPTER

Samuel Crewe, East Cleveland, Ohio, assignor to
 Crewe Manufacturing & Tool Co., Cleveland,
 Ohio

Application February 24, 1948, Serial No. 10,423

1 Claim. (Cl. 222—327)

1

This invention relates to calk guns and particularly to the hand operated type of gun which uses a replaceable cartridge containing the calk.

Conducive to a better understanding of this invention, attention should be directed to my previous United States Patents Nos. 1,883,767; 2,111,582; 2,180,978; and 2,233,587, granted to me on October 18, 1932, March 22, 1938, November 21, 1939, and March 4, 1941, respectively, for calk guns or related apparatus. The two Patents Nos. 2,180,978 and 2,233,587 show manually operable calk guns having plunger operating devices which include internally threaded cups for engaging the metal barrels or cylinders of the guns. These metal barrels are designed primarily to contain bulk calk.

Since the granting of these two patents, it has been found desirable to provide a means whereby calk may be dispersed with these guns without the use of the metal barrel. This is due to the fact that calk made by different manufacturers may be easily purchased in cartridges at almost any hardware store. These cartridges closely resemble the cartridge described and illustrated in my prior Patent No. 2,111,582 and, in addition, each cartridge is provided with a nozzle like the one herein illustrated. These conventional and readily obtainable calk cartridges are quite durable and make unnecessary the use of a permanent barrel and nozzle. They are economical to use and are easily disposed of when empty.

The cartridges made by the different manufacturers, while of the same diameter, nevertheless vary considerably in length. Therefore, when it is desired to use a dispersing mechanism, referred to herein as a plunger operating device, such as the ones shown in my Patents 1,883,767; 2,180,978; and 2,233,587, with a conventional cartridge, provision must be made for adjusting its length so as to receive the particular cartridge obtainable or at hand.

The instant invention therefore provides a means for quickly and easily converting a standard metal barrel type or bulk type calk gun to one adaptable for use with cartridges of different lengths. This is done by simply unscrewing and removing the metal barrel thereof, substituting therefore the herein described attachment, and using it with the previously patented ratchet members.

It is therefore the primary object of this invention to provide an attachment to a plunger operating device which is adaptable for use with calk cartridges of different lengths.

2

Another object is to provide such attachment so that it may be quickly and easily removed from the plunger operating device without the use of special tools or skill, and which attachment will not alter or effect the operating device so that it can not be again used thereafter in its regular way.

A further object is to construct the stated attachment economically and easily out of simple metal stampings, standard and easily obtainable parts.

These and other objects of the invention will become apparent from a reading of the following specification and claim, together with the accompanying drawing in which like parts are referred to and indicated by like reference characters and wherein:

Figure 1 is a side elevation of a calk gun made in accordance with this invention and with parts thereof broken away to show construction;

Figure 2 is a top view of the gun shown in the Figure 1;

Figure 3 is a side elevation of the gun without the calk cartridge;

Figure 4 is a top view of the gun shown in the Figure 3;

Figure 5 is a rear view of the gun shown in the Figure 3;

Figure 6 is a front view of the gun shown in the Figure 3;

Figure 7 is a top view of the back plate of the attachment member unmounted or separate from the ratchet member;

Figure 8 is a front view of the back or rear plate of the attachment member unmounted; and

Figure 9 is a side elevation of the elements shown in the Figures 7 and 8.

Broadly the invention consists of a plunger operating device referred to and indicated as the ratchet member 10; the special attachment constituting the basis of this invention and indicated by the character 20; and the cartridge indicated by the character 40. Each of these elements will be described in detail hereinafter and in the order stated.

The ratchet member 10 consists of a hollow metal handle 11 to which there is pivoted on the pin 13 a trigger element 12 and through which handle there passes a toothed bar or rod 16. The bar 16 is engaged by the trigger 12 and is caused to move forward through the handle 11 when the trigger is pulled or brought rearward proximate to the handle 11. Conventional pawl and dog mechanisms are mounted in the handle to hold the ratchet bar 16 when the trigger is released.

These mechanisms are broadly indicated by the character 14.

The ratchet bar 16 is provided with a simple crosswise grip member 17 to facilitate returning of the ratchet bar to its normal or starting position. This grip member 17 is on the rear end of the bar. The front end of the bar 16 is provided with a plunger or piston head 18 which engages the calk in the cartridge 40 so as to eject it when the ratchet bar is moved forward. The reference character 18a of the Figures 3 and 4 shows the plunger 18 in an alternate position and indicates reciprocal movement thereof.

The front part of the handle 11 supports a cup or socket 15 which receives the rear open end of the cartridge 40. This cup 15 is slightly longer than the piston head 18 and is threaded internally as indicated by the character 19 to firmly engage the metal barrel of the gun when bulk calk is used therein.

The attachment member or cartridge harness 20 consists of a back plate or U-shaped cup-yoke 21 made of suitable stamped metal. It is flat and has a top flange portion 25 which when applied and used rests on the top of the aforesaid cup or socket 15. It has a vertical slot 22 that is open at the bottom and engages the sides of the handle member 11. Two side wings or ears 23 project outwardly and laterally as shown and each wing 23 is perforated and has a hole 24 to receive the rear ends of the side bars 31.

The front plate or U-shaped nozzle-yoke 26 is also made of flat stamped metal. It is somewhat circular and has a diameter closely approximating the diameter of the cartridge 40. It has a slot 27 open at the top for receiving the nozzle 43 of the cartridge. It, similar to the back plate 21, has side wings or ears 28, each of which is provided with a hole 29 for engaging the front ends of the side bars 31.

The two side bars 31 which connect the front and rear plates 26 and 21 respectively are simply pieces of bar metal threaded at each end. The front threaded ends 32 are firmly secured to the side wings 28 of the front plate 26 by means of the hex or square nuts 34. The rear threaded ends 33 are loosely engageable with the side wings 23 of the back plate 21 by means of the wing nuts 35. By tightening or loosening the wing nuts 35, the front plate 26 may be moved closer or farther from the back plate 21 as desired and as needed to accommodate the length of the particular cartridge to be used.

The cartridge 40 is made of durable paper or cardboard formed into a cylinder or tube 41. It has a front cap 42 to which there is attached a nozzle 43, as shown. It has a rear inverted cap 44 made of either paper or light metal which neatly fits the inside of the cylinder 41 and receives the plunger head 18.

To use this device, the ratchet bar 16 is pulled

back as far as it will go or to its starting position; the herein described special attachment is mounted on the handle 11 by simply hooking the back plate 21 over the handle 11 and cup 15. Next, a cartridge 40 is placed between the side bars 31 and its rear or open end inserted in the metal socket 15 so that the inverted cap 44 receives the piston head 18 somewhat as indicated by the element 48a in the Figure 1. Next, the cartridge is straightened out or aligned with the side bars 31 so that the nozzle 43 fits into the slot 27 of the front plate 26. Finally, the wing nuts 35 are tightened sufficiently to draw the front plate rearward to firmly hold the cartridge in the position clearly shown in the Figure 2. When so assembled, the calk may be easily ejected through the nozzle 43 by the simple operation of the trigger 12. When the cartridge is empty, it may be easily removed and replaced on the same manner.

Having thus disclosed the invention in its preferred form, it should be understood that since there may be other forms or modifications of the invention, no limitations thereon are intended except those imposed by the following claim.

I claim:

In combination with a bulk calk gun of the type having a cup adapted to retain a disposable cartridge and a plunger operating device operable through said cup, a cartridge harness, comprising parallel rods adapted to retain a disposable cartridge of calk material in said cup, comprising, a substantially U-shaped cup-yoke engageable with the rear face of said cup and adapted to straddle the operating device, the said cup-yoke having perforated ear portions extending beyond either side of said cup; a substantially U-shaped nozzle-yoke spaced from said cup-yoke and connected thereto by said parallel rods passing through said cup-yoke ear perforations, the said nozzle-yoke being adapted to straddle the nozzle of said disposable cartridge and bear against the front end of said cartridge, and means on the ends of said rods for adjustably spacing the said cup and nozzle yokes for the purpose of retaining the said disposable cartridge therebetween and in anchored attachment to said bulk calk gun cup and plunger operating means.

SAMUEL CREWE.
